TROUSER MEASURING DEVICE

Joseph A. Paranzino, Cherry Hill, N.J., assignor to H. Daroff & Sons, Inc., Philadelphia, Pa., a corporation of Pennsylvania

Filed Oct. 14, 1968, Ser. No. 13,990

Term of patent 14 years

Int. Cl. D10—08

U.S. Cl. D52—6

FIG. 1 is a perspective view of the trouser measuring device showing my new design;

FIG. 2 is a front elevational view thereof;

FIG. 3 is a sectional view taken along the line 3—3 in FIG. 2;

FIG. 4 is a side elevational view thereof;

FIG. 5 is a bottom plan view thereof;

FIG. 6 is a rear elevational view thereof; and

FIG. 7 is a fragmentary front elevational view of the device in its shortest position.

I claim:

The ornamental design for a trouser measuring device, as shown and described.
